UNITED STATES PATENT OFFICE.

JAMES COUPLAND, OF CHICAGO, ILLINOIS.

WINDOW.

Application filed July 23, 1925. Serial No. 45,585.

My invention relates to windows and has among its other objects the provision of window construction which is simple, convenient, durable, attractive and satisfactory for use wherever found applicable. A particular object of the invention is to provide windows which will be substantially fire-proof. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

20 Fig. 1 is a view in elevation of the window embodying the novel features of my invention, the view being taken from the inside of a building;

25 Fig. 2 is a view in elevation of the improved window shown in Fig. 1 as it appears from the outside of the building;

Fig. 3 is a section taken on line 3—3 of Fig. 1;

30 Fig. 4 is a section taken on line 4—4 of Fig. 1;

Fig. 5 is a section taken on line 5—5 of Fig. 2;

35 Fig. 6 is a section taken on line 6—6 of Fig. 5;

Fig. 7 is a section taken on line 7—7 of Fig. 5;

Fig. 8 is a fragmentary perspective view of a sash forming part of my improved window construction;

40 Fig. 9 is a fragmentary perspective view of a member forming part of my improved sash;

Fig. 10 is a fragmentary perspective view of another member forming part of my improved sash;

45 Fig. 11 is a perspective view of a slide forming part of my improved window construction;

50 Fig. 12 is a perspective view of a guide forming part of my improved window construction;

Fig. 13 is a section taken on line 13—13 of Fig. 3; and

Fig. 14 is a section illustrating another form of the invention.

55 Referring to the drawings, my improved window preferably comprises upper and lower window sashes 15 and 16, respectively, the window sashes 15 and 16 being pivotally and slidably mounted in a window casing or frame 17. In the preferred embodiment of the invention, the window casing or frame 17 is formed of metal so as to be substantially fire-proof.

As illustrated, the window casing 17 preferably comprises a top member 19, side members 20 and 21 and a sill member 23. As

best shown in Fig. 3, each of the side members 20 and 21 comprises a plate 24 having a laterally extending flange 25. Extending laterally from each flange 25 is a rib or flange 26. The flanges 26 project outwardly from the window and the marginal portions of the flanges 25 are imbedded in brick-work 27, or the equivalent, surrounding the window casing 17. The top member 19

70 comprises a plate 30 having an upwardly extending flange 31 which is aligned with the flanges 25 of the side members 20 and 21. Projecting outwardly from the flange 31 is a flange 32, the outer edge of which is substantially flush with the outer edges of the flanges 26.

Mounted integral with the plate 30 are side flanges 34 whereby the top member may be rigidly secured to the

75 plates 24, bolts or rivets 35 being provided for this purpose. The sill member 23 is formed of a plate 37 having a downwardly

80 projecting front flange 38 and downwardly projecting side flanges 39. Bolts or rivets 40 rigidly secure the side flanges 39 to the

85 plates 24.

The side members 20 and 21, the top member 19 and the sill member 23 are

90 preferably formed from pressed steel, or the equivalent, and in the preferred embodiment of the invention are protected from the elements by moulding members 42 and

95 a sill cover 43, the moulding members 42 and the sill cover 43 being formed of some suitable metal which does not readily corrode or deteriorate when exposed to the elements.

As shown, each moulding member 42 may be formed with a groove 44 adapted to receive the outer edge of the flange 32 or

100 one of the flanges 26 (Figs. 3 and 5). Each

55

105

molding member 42 is also preferably formed with a flange 46 whereby the moulding member may be secured to the top member 19 or to one of the side members 20 and 21; the flange being secured to said top or side members by bolts or screws 47. The bolts or screws 47 are also employed to secure stops 48 to the top member 19 and the side members 20 and 21. Each stop 48 is preferably provided with a groove 49 adapted to accommodate the flange 46 of one of the moulding members 42. The stops 48 are also preferably formed from metal which does not readily corrode. The inner side of the window is finished with upper and lower stops 50 and 51, respectively, and side stops 52 (Figs. 3 and 5).

In some instances, I may prefer to form the members 19, 20, 21 and 23 from stain-
20 less steel or the like so that the moulding members and the sill cover may be omitted from the construction.

Arranged intermediate the window sashes 15 and 16 and secured to the side members 25 20 and 21 are parting strips 54. Aligned with the parting strips 54 and secured to the top member 19 is a parting strip 55. Referring to Fig. 6, it will be noted that the parting strips 54 are employed to hold 30 the sill cover 43 in place upon the sill member 23, the sill cover 43 being provided with upwardly extending flanges 57 which are inserted between the parting strips 54 and the side members 20 and 21.

35 The window sashes 15 and 16 are preferably formed from metal and in the preferred embodiment of the invention each sash comprises substantially identical upper and lower bars 59 and substantially identical side bars 60, the bars 59 and 60 being provided with channels or grooves 62 and 63, respectively, which open toward the inner side of the window (Figs. 3 and 6). As best shown in Fig. 6, the ends of the grooves 45 62 and 63 are so formed that they accommodate substantially L-shaped members 64, the bars 59 and 60 being secured to the L-shaped members by screws or bolts 65. The bars 59 and 60 are provided with inwardly extending flanges 67 adapted to receive window panes 69. The window panes 69 are secured in the window sashes 15 and 16 by means comprising angle bars 70 and 74 (Figs. 8, 9, and 10). Each angle bar 50 55 70 is provided with a plurality of slots 77 which permit the angle bar to be detachably secured in the window sash. The angle bars 70 and 74 may be cut any suitable length and may be matched at the corners, as illustrated in Fig. 8. The angle bars 74 are secured to the window sashes by screws 78 or the equivalent.

60 When the window pane 69 is to be mounted in one of the window sashes, a thin layer of 65 putty is first applied to the inner sides of

the flanges 67 and then the window pane is brought into position against the putty. The angle bars 70 are then secured to the window sash to hold the window pane in place, strips of rubber 80 or other resilient material being preferably inserted between the angle bars 70 and the window pane. The angle bars 74 are then secured to the window sash. It will be noted that the angle bars 74 close the grooves 62 and 63 and also prevent moisture from entering between the angle bars 70 and the bars 59 and 60.

As hereinbefore set forth, the window sashes 15 and 16 are slidably and pivotally mounted in the window casing 17, the window sash 15 being associated with slides 82 and 83, and the window sash 16 being associated with slides 84 and 85 (Fig. 3). The slides 82, 83, 84 and 85 are mounted in guides 86 which are fixed to the side members 20 and 21. The guide members 86 preferably extend from the top member 19 to the sill member 23 and are formed from sheet metal. As shown in Fig. 12, the guides 86 are substantially channel-shape 90 in cross section to provide inwardly extending flanges 87 which are turned over at the outer edges, as indicated at 88, to engage the slides 82, 83, 84 and 85. These several slides are substantially identical in form and 95 each preferably comprises a sheet metal tube 89 having a slot 90 extending longitudinally thereof. Each end of the tube 89 is reinforced by a block 91. Secured to the inner surface of each tube 89 and adapted to 100 project through the slot 90 thereof are leaf springs 93 adapted to frictionally engage the associated guide 86 to hold the associated window sash in any desired position intermediate its extreme positions. Secured to the slide 85 is a plate 95 to which is hinged a plate 96, which may be swung into the position wherein it is shown in dotted lines in Fig. 3. The plate 96 is formed with a laterally extending flange 99 having an inwardly extending rib 100, the flange 99 and the rib 100 cooperating to seal the free edge of the window sash 16 when the window sash 16 is in its closed position. Secured to the slide 84 is a plate 95^a which is substantially identical in construction to the plate 95 and has hinged to it a plate 102. The sash 16 is rigidly secured to the plate 102 by any suitable means and may be swung into the position wherein it is shown in dotted lines in Fig. 4, the free edge of the sash being beveled as at 104.

Secured to the slide 83 is a plate 96^a having a laterally extending flange 99^a which is formed with a rib 100^a, the flange 99^a and the rib 100^a cooperating to seal the free edge of the window sash 15 when the window sash 15 is in its closed position. Secured to the slide 82 is a plate 105 having a laterally extending flange 106 which is

hinged at 108 to a laterally extending flange 109 of a plate 110, the window sash 15 being rigidly secured to the plate 110. Obviously, the window sash 15 may be swung 5 into the position in which it is shown in dotted lines in Fig. 4.

It will be readily understood that the hinged plate 96 with its flange 99 and its rib 100 permit the window sash 15 to be 10 swung into the position wherein it is shown in dotted lines in Fig. 4 when the sash 15 is positioned in the lower part of the window casing 17 as the plate 96 may be 15 swung in the position wherein it is shown in dotted lines in Fig. 3 if the window sash 16 is first brought in the position wherein it is shown in dotted lines in Fig. 4. This construction is similar to the construction which I have illustrated and described in 20 United States Letters Patent No. 1,542,373, dated June 16, 1925, and it need not be described in detail in this application.

The free edges of the window sashes 15 and 16 may be detachably secured to the 25 slides 83 and 85, respectively, by means comprising latch member 112, which are more fully shown and described in my aforementioned United States Letters Patent (Fig. 1). To lock the window sash 15 in a lowered 30 position and to lock the window sash 16 in a raised position, I preferably provide locking bolts 115 and 115^a, respectively, (Fig. 3). The locking bolts 115 and 115^a are preferably mounted in a housing member 35 117 secured to the side member 20 and are adapted to pass through apertures 118 formed in the side member 20. The slides 82 and 84 are provided with holes 120 into which the locking bolts 115 and 115^a will 40 enter when the holes register with the apertures 118, the locking bolts 115 and 115^a being urged into the holes 120 by compression springs 122 mounted in the housing member 117. The locking bolts 115 and 115^a are 45 provided with extensions 123 which project through the stop 52 in such manner that they may be depressed to retract the locking bolts from the holes 120 against the action of the springs 122.

50 Referring now to Fig. 5, I preferably secure a weather strip 125 to the window sash 15, which weather strip is adapted to engage a weather strip 126, secured to the window sash 16, when the window sashes are in their 55 closed positions. The weather strips 125 and 126 are preferably formed from strips of metal having some resiliency.

In Fig. 14, I have illustrated the manner 60 in which the side members 20 and 21 may be made from a sheet of metal if it is so desired. In this instance, the side member is formed with a plate 24^a, which is substantially identical with the aforementioned plates 24. Formed integral with the plate 65 24^a and extending laterally therefrom is a

flange 25^a which is folded intermediate its ends to form a flange 26^a corresponding to the aforementioned flanges 26.

Having thus described my invention, it is obvious that various immaterial modifications may be made in the same without departing from the spirit of my invention; hence I do not wish to be understood as limiting myself to the exact form, construction, arrangement and combination of parts 70 herein shown and described, or uses mentioned.

What I claim as new and desire to secure by Letters Patent is:

1. A window casing comprising side members having laterally extending flanges, ribs 80 extending laterally from said flanges, and a top member secured to the side members and provided with a rib extending substantially flush with said first-mentioned ribs. 85

2. A window casing comprising a plurality of rigid metallic side members secured to each other, and a metallic top member secured to the side members and metallic covers for protecting said members to prevent 90 corrosion thereof.

3. A window casing comprising a pair of metallic side members, a metallic top member secured to the side members, and a metallic sill member secured to the side members, each of the side members being provided with a flange extending in the plane 95 of the casing, and a rib extending laterally from the flange and spaced from its free edge. 100

4. A window casing comprising a pair of metallic side members, a metallic top member secured to the side members, a metallic sill member secured to the side members, moulding members of thin sheet metal protecting the side members and the top member, and a cover of thin sheet metal for the sill member. 105

5. A window casing comprising metallic side members having flanges extending in the plane of the window, said flanges having integral ribs formed thereon and projecting at an angle thereto, and a metallic top member secured to the side members and having a flange forming a continuation of the first-mentioned flanges, said flange of said top member having a rib extending substantially flush with the first-mentioned ribs. 110 115

6. A window casing comprising a pair of metallic side members, a metallic top member secured to the side members, a metallic sill member secured to the side members, molding members of thin sheet metal protecting the side members and the top member, metal strips protecting the edges of the molding members, and a covering of thin sheet metal for the sill member. 120 125

7. A window casing comprising metallic side members having flanges extending in the plane of the window, said flanges having 130

integral ribs formed thereon and projecting at an angle thereto, and a metallic top member secured to the side members and having a flange forming a continuation of the first-mentioned flanges, said flange of said top member having a rib extending substantially flush with the first-mentioned ribs, a metallic sill member secured to the side mem-

bers, molding members of thin sheet metal protecting the side members and the top ¹⁰ member, metal strips protecting the edges of the molding members and a covering of thin sheet metal for the sill member.

In testimony whereof, I have hereunto signed my name.

JAMES COUPLAND.
